UNITED STATES PATENT OFFICE.

BERTON E. FIELD, OF MILLER, SOUTH DAKOTA, ASSIGNOR OF ONE-THIRD TO WILLIAM A. PETERSON, OF MILLER, SOUTH DAKOTA.

GATE.

1,129,386.

Specification of Letters Patent. Patented Feb. 23, 1915.

Application filed April 8, 1914. Serial No. 830,483.

To all whom it may concern:

Be it known that I, BERTON E. FIELD, citizen of the United States, residing at Miller, in the county of Hand and State of 5 South Dakota, have invented certain new and useful Improvements in Gates, of which the following is a specification.

This invention relates to improvements in gates, more particularly to the class of farm 10 gates which are operable from a distance by a person approaching in a vehicle or upon horseback, and has for one of its objects to provide a simply constructed device which is partly automatic in its action and which may 15 be opened or closed by a slight operation of a pulling device.

With these and other objects in view the invention consists in certain novel features of construction as hereinafter shown and de- 20 scribed and then specifically pointed out in the claim; and in the drawings illustrative of the preferred embodiment of the invention Figure 1 is a side elevation of the gate and an end elevation of the operating means 25 illustrating the construction and operation. Fig. 2 is a side elevation of the operating means with the gate in section on the line 2—2 of Fig. 1. Fig. 3 is a view similar to Fig. 2 showing the gate in open and tilted 30 position. Fig. 4 is a plan view of the im- proved apparatus with the gate in closed position. Fig. 5 is a detached perspective view of the tilting member. Fig. 6 is a de- 35 tached perspective view of the keeper for the tilting member.

Corresponding and like parts are referred to in the following description and indicated in all the views of the drawings by the same reference characters.

40 The improved gate operating apparatus includes a relatively tall post 10 located at the hinge side of the gateway opening and another post 11 which may be shorter than the post 10, and located at the latch side of the gateway opening. Connected to the post 45 10 is a hanger device represented as a whole at 12 and formed with a guideway 13. A tilting bracket forms a part of the improved device and includes an upper member 14 with downturned ends 15 and a rear member 16, the latter being of less width than the ends 15 and operates through the seat or cavity 18 of the hanger member 12. The hanger bracket is thus slidably disposed rel- 50 ative to the post 10 within the range of the member 12—13.

The gate may be of any suitable construction, and it is not desired therefore to limit the invention in this respect, but for the purpose of illustration a conventional gate is 60 shown including vertical end terminals 17—18, horizontal rails 19 and a brace 20. At its lower end the member 17 is provided with a stud 21 which is mounted for rotation in a step 22. At its upper end the member 65 17 is provided with an upwardly directed pin 23 which extends through an aperture or bearing in the upper member 14 of the tilting bracket.

Pivoted at 24 to the post 10 is a lever arm 70 25 extending at its lower end at 26 through a bearing or seat in the member 14 of the tilting bracket. Pull cables or other suitable devices are connected to the lever 25 at its upper end as represented at 27 and ex- 75 tending in opposite directions to a sufficient distance to enable them to be actuated from a vehicle or on horseback by a person ap- 80 proaching from a distance. To this end guide posts 28 are located at convenient points to carry the members 27 and support them in convenient position for use.

When the gate is in closed position, the 85 tilting bracket will be maintained in hori- 90 zontal position as shown in Fig. 2, while the lever 25 will be in vertical position, or substantially in vertical alinement with the gate. If it is desired to open the gate one 95 of the members 27 is actuated to cause the lever 25 to swing upon its pivot 24 and thus 95 carry the tilting bracket to one side or the other through the action of the pin 26, as represented in Fig. 3. This movement will 100 tilt the gate to one side and throw it off its balance and cause it to swing into open posi- 105 tion, and the gate may thus be caused to swing in either direction by simply swing- 110 ing the lever 25 from one side to the other. When the gate is in closed position a pull 115 upon the cable at one side of the gateway opening will cause it to swing into open po- 120 sition, then when it is desired to close the gate it is only necessary to reverse the posi- 125 tion of the lever 25. A latch device 29 is connected at 30 to the member 18 of the gate and adapted to automatically engage 130 with the keeper 31 upon the post 11, and as the gate swings into closed position the latch

29 will automatically engage with the keeper and thus prevent the gate from swinging past the latch post, as will be obvious. A pull wire or like device 32 is connected to the latch member 29 and extends thence over suitable guide pulleys 33 and over the posts 28 in convenient position for the person approaching the gate, who will first actuate the pull member 32 to release the latch 10 and then actuate the member 27 to tilt the gate to cause it to open. Posts 34 are located at opposite sides of the gateway opening in the path of the gate when it is swung into open position and provided with 15 catches 35 adapted to be engaged by loops or like devices 36 on the gate when the gate is swung into open position, and thus lock the gate open. When the gate is to be closed a pull upon the member 27 will first 20 elevate the outer end of the gate and release the loop from the catch. The tilting bracket and the guide member are preferably as light as possible consistent with the strains to which they will be subjected when in use.

25 The improved device is simple in construction, can be inexpensively manufac-

tured and applied without material structural change to gates of various sizes and constructions.

Having thus described the invention, 30 what is claimed as new is:

In an apparatus of the class described, a hinge post, a hanger device carried by said post and provided with a transverse guide-way, a bracket including a vertical member 35 and a horizontal member spaced apart, the vertical member being slidable in said guide-way and the horizontal member having sockets spaced apart, a gate including an end member having a stud engaging one of the 40 sockets of the horizontal member of said bracket, a lever pivoted to said post and engaging at one end in the other socket of said bracket and operative to move the bracket and the gate coupled thereto transversely of 45 the hanger device and the post.

In testimony whereof I affix my signature in presence of two witnesses.

BERTON E. FIELD. [L. S.]
